CLAIM

The ornamental design for a fryer tray carrier with cross-braced support, as shown and described.

DESCRIPTION

FIG. 1 is a rear perspective view of a fryer tray carrier with cross-braced support according to my design;

FIG. 2 is a side view of a fryer tray carrier with cross-braced support, as shown in FIG. 1, the opposite side view being a mirror image thereof;

FIG. 3 is a rear view of a fryer tray carrier with cross-braced support, as shown in FIG. 1;

FIG. 4 is a bottom view of a fryer tray carrier with cross-braced support, as shown in FIG. 1;

FIG. 5 is a front perspective view, the broken line showing of a fryer is for illustrative purposes only and forms no part of the claimed design; and,

FIG. 6 is a top view of a fryer tray carrier with cross-braced support, as shown in FIG. 1.
